Attley.

UNITED STATES PATENT OFFICE.

FRANK A. RYTHER, OF CHICAGO, ILLINOIS, ASSIGNOR TO INTERNATIONAL HARVESTER COMPANY OF NEW JERSEY, A CORPORATION OF NEW JERSEY.

GRAIN-BINDER.

1,216,368.

Specification of Letters Patent. Patented Feb. 20, 1917.

Application filed April 7, 1916. Serial No. 89,682.

To all whom it may concern:

Be it known that I, FRANK A. RYTHER, a citizen of the United States, residing at Chicago, in the county of Cook and State of Illinois, have invented certain new and useful Improvements in Grain-Binders, of which the following is a full, clear, and exact specification.

My invention relates to grain binders.

Its object is to provide an improved form of clutch tripping and compressor mechanism therefor. A further object of my invention is to provide a simple and efficient construction for the purpose indicated, whereby all difficulty with repeating of the binding mechanism is effectually overcome.

One embodiment of the invention is shown for purposes of illustration in the accompanying drawings, in which—

Figure 1 is a front end elevation of a grain binder having my invention embodied in its construction.

Fig. 2 is a similar view showing a modified form of part of the details of construction illustrated in Fig. 1.

Fig. 3 is a side elevation of parts of Fig. 1 as seen in the direction of arrow *a*.

Fig. 4 is a cross section of a part of Fig. 3 along the line *b*—*b*.

In the construction illustrated, 1 represents an end member of a common form of U-shaped binder frame having a lower tubular member 2, in which is journaled the needle shaft 3 and an upper tubular member (not shown), in which is journaled the knotted shaft 4 having the cam wheel 5 secured to its front end, 6 the packer shaft journaled in bearings carried by the lower part of the frame, 7 a clutch member secured to the packer shaft and adapted to intermittently engage with the clutch pawl 8 carried by a shaft 9 on a pinion which is journaled upon the packer shaft and meshing with a pinion 10 secured to the lower end of a shaft journaled in the end member 1 of the frame and having a pinion 11 secured to its opposite end and meshing with the cam wheel 5. 12 represents a crank arm integral with one end of the needle shaft 3 and having the needle 13 secured to its opposite end, and 14 a pitman connecting the crank arm with the cam wheel, 15 a lever pivoted intermediate its ends upon the binder frame having a roller 16 journaled

with the cam track 17 on the cam wheel 5, and 18 a link pivotally connected with the opposite end of the lever. 19 represents a clutch tripping and compressor rock shaft journaled in bearings carried by the binder frame having an arm 20 secured to one end, upon which is adjustably mounted a combined clutch tripping and compressor arm 21 and a crank arm 22 at its opposite end, and 23 the binder deck inclined downward toward the arm 20.

All of the above mentioned parts are common in grain binder construction. My improved form of clutch tripping and compressor mechanism includes an eccentric collar 24 that receives the needle shaft 3 adjacent the crank arm 12 and having laterally extending lugs 25 integral therewith that engage with opposite sides of the crank arm whereby the collar is rocked with the shaft. 70 Journaled upon the eccentric collar is a clutch tripping arm 26 provided with a short sleeve member 27 on its free end that slidably receives one end of a clutch pawl engaging member having a downwardly 80 turned head 28, the opposite end of said member being slidably received by an opening in an ear member 29 integral with the arm 26, and 30 represents a buffer spring encircling the body of the pawl engaging 85 member and operative between the ear and a pressure controlling nut 31 in a manner to cushion the force of engagement of the clutch pawl 8 with the head 28. 32 represents a laterally extending lug on the side 90 of the arm 26 that is adapted to engage with a fixed lug 33 on the binder frame in a manner to limit a turning movement of the arm in a direction to engage the pawl 8. The arm 26 is provided with a depending arm 34 below its axis whereby it is flexibly connected with the lower end of a yoke member 35, which is provided at its upper end with an adjusting sleeve 36 threaded in the end wall of the yoke and 100 slidably receiving the body of the link 18. Secured to the body of the link 18, and adjacent the upper end wall of the yoke, is a rocking collar 37 having notches in its side walls whereby it slidably engages the 105 side walls of the yoke and against which bears one end of a compression spring 38 encircling the link 18 and having its opposite end received by a cup-shaped collar 39 secured to the lower end of the link 18 and 110

slidably engaging with the side walls of the yoke below a bridge member 40 operative to limit a longitudinal movement of the yoke and link relative to each other. The 5 yoke member 35 is provided with a laterally extending arm 41 having an elongated opening 42 therein that receives the crank arm 22, and a journal bearing 43 for the shaft 19 upon the frame adjacent the crank arm is 10 correspondingly elongated, permitting a free operation of the associated parts of the mechanism when performing their function of clutch tripping and bundle compressing.

A modified form of yoke connecting the 15 arm 34 with the lever 15, illustrated in Fig. 2, includes a link 44 having its upper end pivotally connected with the lever 15 and its lower part threaded to receive upper and lower adjusting nuts 45 and 46, respectively, 20 spaced apart upon the link longitudinally, the body of the link between the nuts being slidably received by an ear member 47 integral with a sleeve 48 secured to a companion parallel link 49 having its upper end adjustably secured, by means of nuts 50, to an 25 ear 51 integral with a sleeve 52 slidable longitudinally upon the link 44, and 53 represents a compression spring encircling the body of said link and operative between 30 the sleeve 52 and the nut 45 in the same manner as the spring 38. The lower end of the link 49 is provided with an opening that receives the crank arm 22 of the shaft 19, and 54 represents a link flexibly connecting the crank arm with the arm 34 of the clutch tripping arm 26.

In operation, with the mechanism in the position shown in Fig. 1, the grain is packed against the arm 21 and after increase 40 of pressure it is gradually drawn outward, rocking the shaft 19 in its bearings and drawing down upon the yoke 35 against the force of the spring 38, which is regulated by means of the threaded sleeve 36, and, 45 through the pivotal connection of the lower end of the yoke with the arm 34, rocking the clutch tripping arm 26 upon the eccentric collar 24 until its free end is moved sufficient to carry the head 28 out of engagement with the nose of the clutch pawl 8, which immediately engages with the clutch member 7 secured to the constantly rotatable 50 packer shaft 6, whereby motion is imparted to the cam wheel 5 and, through its pitman 55 connection with the crank arm 12, it rocks the needle shaft 3 in its bearings, turning the eccentric collar 24 in a direction to carry the arm 26 away from the clutch pawl and retaining it in a disengaged position 60 until the binding mechanism has completed its cycle of movement and the needle returns to its initial position, the arm 26 carrying the head 28 back to its position of engagement with the clutch pawl 8. The 65 arm 26 turns about the axis of the needle

shaft upon the eccentric collar 24 during its clutch tripping movement and the collar, in turning below the needle shaft, moves it bodily upward and toward the clutch pawl, swinging the yoke 35 toward the axis of the needle shaft, the elongated opening 42 in the arm 41 or the flexible connection, by means of the link 54, permitting a free movement of the associated parts of the mechanism.

Having shown and described an embodiment of my invention, I do not desire to have it limited to the specific details of the structure as illustrated, it being understood that changes may be made in the form, proportion and organization of its various parts without departing from the spirit of the invention as indicated in the appended claims.

What I claim as my invention and desire to secure by Letters Patent is:

1. A grain binder including, in combination, a power transmission gear mechanism including a clutch, a needle shaft, a clutch tripping arm, and automatically operative means for moving said arm axially and 90 bodily toward or from said clutch.

2. In a grain binder, power transmission gear mechanism including a clutch, a needle shaft, a clutch tripping arm journaled on said shaft, means on said shaft for controlling the movement of said arm, a compressor trip shaft, and an operative connection between said shaft and trip.

3. In a grain binder, power transmission gear mechanism including a clutch, a needle 100 shaft, a cam rotatable therewith, a clutch controlling member carried on said shaft and engageable with said cam, a compressor trip shaft, a crank on said controlling member, and a pivotal connection between said 105 crank and said trip.

4. A grain binder including, in combination, a power transmission gear mechanism including a clutch, a rocking needle shaft, means operatively connecting said needle 110 shaft with said power transmission gear mechanism, an eccentric collar secured to said needle shaft, and a clutch tripping arm journaled on said eccentric collar whereby said arm is moved axially and bodily toward or from said clutch when said needle shaft is rocked.

5. A grain binder including, in combination, a binder frame, a power transmission gear mechanism, a rocking needle shaft journaled on said frame and operatively connected with said power transmission gear mechanism, an eccentric collar secured to said needle shaft, a clutch mechanism forming part of said power transmission gear mechanism 125 and including a clutch pawl, and a pawl engaging arm journaled upon said eccentric collar whereby said arm is moved axially and bodily toward or from said pawl when said needle shaft is rocked, said arm en- 130

gaging with a fixed part of said frame in a manner limiting an axial movement thereof in one direction.

6. A grain binder including, in combination, a binder frame, a power transmission gear mechanism including a clutch mechanism, said clutch mechanism including a clutch pawl, a rocking needle shaft journaled on said frame and operatively connected with 10 said power transmission gear mechanism, clutch tripping mechanism including a rock shaft journaled on said frame and provided with a grain resisting element at one end and a crank arm at its opposite end, means

permitting said crank arm to move bodily 15 toward the axis of said needle shaft, a cam controlled lever pivoted upon said frame, a vertically disposed longitudinally yielding yoke having its upper end pivotally connected with said lever and its opposite end provided with an elongated opening receiving said crank arm, an eccentric collar secured to said needle shaft, and a pawl engaging arm journaled upon said collar and provided with an arm having a pivotal connection with the lower end of said yoke. 20 25

In testimony whereof I affix my signature.
FRANK A. RYTHE.
